Chinese Office Action, First Notification to Make Rectification, dated Nov. 28, 2018 for Application No. CN 201830489110.8, 1 pg.

Primary Examiner — Janice Hallmark*Assistant Examiner* — Omeed Agilee(74) *Attorney, Agent, or Firm* — Frost Brown Todd LLC(57) **CLAIM**

The ornamental design for a bulk sample tray, as shown and described.

DESCRIPTION

FIG. 1 is a top perspective view of a bulk sample tray, showing our new design;

FIG. 2 is a bottom perspective view thereof;

FIG. 3 is a front elevational view thereof;

FIG. 4 is a back elevational view thereof;

FIG. 5 is a left elevational view thereof;

FIG. 6 is a right elevational view thereof;

FIG. 7 is a top plan view thereof; and,

FIG. 8 is a bottom plan view thereof.

The broken lines in the drawings depict portions of the bulk sample tray that form no part of the claimed design.
